CLAIM

The ornamental design for an electronic device, as shown and described.

DESCRIPTION

FIG. 1 is a front perspective view of an electronic device showing our new design according to a first embodiment; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; FIG. 7 is a bottom plan view thereof; FIG. 8 is a rear perspective view thereof; FIG. 9 is a front perspective view of an electronic device showing our new design according to a second embodiment; FIG. 10 is a front elevation view thereof; FIG. 11 is a rear elevation view thereof; FIG. 12 is a left side elevation view thereof; FIG. 13 is a right side elevation view thereof; FIG. 14 is a top plan view thereof; FIG. 15 is a bottom plan view thereof; FIG. 16 is a rear perspective view thereof; FIG. 17 is a front perspective view of an electronic device showing our new design according to a third embodiment; FIG. 18 is a front elevation view thereof;

(Continued)

FIG. 19 is a rear elevation view thereof;
 FIG. 20 is a left side elevation view thereof;
 FIG. 21 is a right side elevation view thereof;
 FIG. 22 is a top plan view thereof;
 FIG. 23 is a bottom plan view thereof; and,
 FIG. 24 is a rear perspective view thereof.
 The evenly dashed broken lines in the drawings illustrate portions of the electronic device that form no part of the claimed design. The dot-dash broken lines in the drawings define the boundary of the claimed design and form no part thereof.

1 Claim, 24 Drawing Sheets
